(57) **CLAIM**

We claim the ornamental design for a towel, as shown and described.

DESCRIPTION

FIG. 1 is a perspective view showing our new design for a towel.

FIG. 2 is a top view of our new design shown in FIG. 1; and, FIG. 3 is a cross-sectional view take along the 3—3 in FIG. 2. The broken lines are for environmental purposes only and form no part of the claimed design.
